UNITED STATES PATENT OFFICE.

EDWARD T. ROBINSON, OF ST. LOUIS, MISSOURI, ASSIGNOR TO ST. LOUIS CAR COMPANY, OF ST. LOUIS, MISSOURI, A CORPORATION.

DOOR HANGER AND GUIDE.

No. 926,356.

Specification of Letters Patent.

Patented June 29, 1909.

Application filed October 5, 1908. Serial No. 456,294.

To all whom it may concern:

Be it known that I, EDWARD T. ROBINSON, a citizen of the United States of America, residing at the city of St. Louis, in the State of Missouri, have invented certain new and useful Improvements in Door Hangers and Guides, of which the following is a full, clear, and exact description, reference being had to the accompanying drawings, forming 10 part of this specification.

My invention relates to a new and useful improvement in door hangers and guides and is designed particularly for use in vestibule doors for passenger cars.

15 The object of the invention is to support and, where sectional doors are employed, to guide the door section farthest away from the section which is hinged to a post adjacent to the door opening, in such manner 20 that the weight of the plurality of door sections is not entirely carried by the hinges which support the doors on the posts just mentioned.

Figure I is a horizontal section of a portion of a vestibule of a car showing my invention applied thereto. Fig. II is a side elevation, partly broken away, of a portion of the vestibule of a car together with my invention applied thereto. Fig. III is a 30 perspective view of a portion of a door, my improved hanger and a portion of a supporting and guiding rail employed in carrying out my invention.

A designates the vestibule of a car which 35 is provided with a door opening at one side, said door opening being formed between the platform B and the hood C and the platform post D and the corner post E of the car opening. This door opening is designed to 40 be closed by means of a plurality of hinged door sections 1, 2, 3 and 4, the former of which is hinged at its inner edge to the platform post D, while the section 2 is hinged at its outer edge to section 1, section 3 is hinged 45 at its inner edge to section 2 and section 4 is hinged at its outer edge to section 3, the hinged connection between the various sections being so arranged that the door can be folded compactly at the inner side of the 50 platform post D into the position shown in dotted lines, Fig. I. That is, that they can be folded face to face and occupy a minimum amount of space.

5 designates a guide-rail or supporting

track which is arranged above the door sections and is supported within the vestibule of the car in any suitable manner, such as by means of hanger brackets 6. The guide rail extends from the corner post E and is gradually curved inwardly to a point in 60 rear of the platform post D where it is provided with an outwardly projecting transverse arm 5^a extending to the platform post D, which in length corresponds to the width approximately of the folded sections. The 6 guide rail 4 is provided with a vertical longitudinal slot 7 extending from the corner post E to the arm 5^a.

8 designates a T-hanger secured to the door 4, and provided with a plurality of 7 rollers, preferably three in number. One of these rollers 9, is vertically disposed and is designed to operate in the slot 7 of the rail 5 while the other two rollers 10—10 are horizontally disposed and rest, and are designed to ride upon the upper face of the rail 5 at each side of the slot 7.

It will be seen from the construction just described, that when the door proper which is composed of the hinged sections, is opened 8^a to the position shown in dotted lines, Fig. I, of the drawing, that the door sections are guided to that position and that the hinges which secure the section 1 to the platform post D are relieved of a great portion of the 8^b weight of the door proper, by the guide and supporting rail 5 through the instrumentality of the hanger 8, and that the rollers 9 and 10—10 make the coöperation between the hanger and rail antifrictional. 9^c

I claim:

The combination, with a vestibule having a door opening, a corner post at one side, and a platform post at the other side of the opening; of a gradually curved guide rail 9 having a transverse arm at one end and a longitudinal slot extending from the corner post to the arm, and secured to the vestibule over the opening, and a sectional door hinged to the platform at one end and provided 1 with a T-bracket at its other end whereby it is supported and guided by the guide rail to a folded condition beneath the arm of the guide rail against the platform post.

EDWARD T. ROBINSON.

In the presence of—

LILY ROST,
EDNA LINN.
